UNITED STATES PATENT OFFICE.

WILFRED SAMPSON SAMUEL, OF LONDON, ENGLAND.

TALKING-MACHINE.

1,239,305.

Specification of Letters Patent.

Patented Sept. 4, 1917.

Application filed February 3, 1915. Serial No. 5,907.

To all whom it may concern:

Be it known that I, WILFRED SAMPSON SAMUEL, residing at 32 Worship street, London, E. C., England, Great Britain, have 5 invented a certain new and useful Improvement in Talking-Machines; and I do hereby declare the following to be a full, clear, and exact description of the invention, such as will enable others skilled in the art to which 10 it appertains to make and use the same.

This invention relates to improvements in gramophones or like talking machines of the type known as the "deflector" or "reflex" type, in which the usual large horn 15 or trumpet is replaced by a deflector opposite to which the conduit or small trumpet leading from the tone arm is situated.

It is well known in connection with talking machines that it is desirable as far as 20 possible that dust and foreign matter should not be allowed to enter the tone arms and fittings. For this purpose it has already been proposed in machines of this character to construct the machine in such a manner 25 that the outer continuity of the connection between the sound-box and trumpet need never be broken.

The object of the present invention is to 30 devise an improved form of machine of the above character, and the invention consists of the combination in a talking machine of the type referred to, of a casing, a cover 35 hinged thereon, a deflector arranged with its axis transverse to said cover, a trumpet secured to said deflector and with one end in alignment with the axis of said deflector, a tone arm universally jointed to the other end of said trumpet and means for retaining 40 said tone arm within the cover when required.

In the accompanying drawing, which 45 illustrates one method of carrying the invention into effect as applied to a gramophone,

Figure 1 is a perspective view showing the gramophone in its open position, Fig. 2 is an elevation showing the tone arm in the position for closing the cover, and Fig. 2^a is an enlarged side elevation partly 50 in section, of the trumpet and tone arm.

A casing A carrying the motor, etc., and the turn table B has hinged to it a cover C by means of hinges C¹. The cover is maintained in its open position by means of a strut C². A deflector D provided with flanges D¹ is secured in the cover C by screws

E in the manner shown at E¹. The deflector is made of metal, and is bowl shaped, and in face view with the flanges is rectangular. Secured within the bowl of the deflector is 60 a hollow member or short trumpet F, the upper open end of which is positioned a short distance from the bowl and in alignment with its axis. The member F is secured by brackets F¹ as shown. The hollow 65 member is flared at its upper end and the lower end is provided with a hollow T piece G. The member G is held in the member F so as to turn by means of the pin f on the trumpet engaging the groove g in the member G, and has a cylindrical sleeve G¹ in which the tone arm H has its bearing. The tone arm H is therefore universally jointed 70 with respect to the member or trumpet F. The sleeve G¹ is provided with a slot K, and secured to the tone arm and passing through the slot K is a thumb screw K¹. The tone arm H carrying the sound box L is shaped 75 as shown in Fig. 2 to which position the tone arm can be moved to change a needle 80 or record.

The gramophone when in use is as shown in Fig. 1. When it is desired to close the machine, the tone arm H is moved to the position shown in Fig. 2, where it is housed 85 within the deflector D. It is secured in this position by means of the thumb screw K¹. The cover C can now be closed down. It will be seen that the machine can be closed 90 without detaching the tone arm or sound box.

Various modifications can be made in the manner of carrying this invention into effect. For instance the hollow member or trumpet 95 F can be secured in or near the deflector in any suitable manner other than that shown, and other means of locking the tone arm in position may be employed. The deflector can be made of any suitable material such as wood, papier mâché, vulcanite or 100 the like, and could itself act as a cover.

Having thus described my invention, what I claim as new and desire to secure by Letters Patent is:

1. In a talking machine of the type referred to, the combination of a casing, a cover hinged thereon, a bowl shaped deflector mounted in said cover and arranged with its axis transverse to said cover, a trumpet secured to said deflector and with one end in alignment with the axis of said deflector, a tone arm universally jointed to 105

110

the other end of said trumpet and means for retaining said tone arm within said deflector when required.

2. In a talking machine of the type referred to, the combination of a casing, a cover hinged thereon, a bowl shaped deflector mounted in said cover and arranged with its axis transverse to said cover, a trumpet secured to said deflector and with 10 one end in alinement with the axis of said deflector, a hollow T piece pivoted to the other end of said trumpet, a tone arm having one end pivoted to said hollow T piece, and means for retaining said tone arm within 15 said deflector when required.

3. In a talking machine of the type referred to, the combination of a casing, a cover hinged thereon, a bowl shaped deflector mounted in said cover and arranged 20 with its axis transverse to said cover, a trumpet secured to said deflector and with one end in alinement with the axis of said deflector, a hollow T-piece pivoted to the other end of said trumpet, a tone arm hav-

ing one end pivoted to said hollow T-piece 25 and means for clamping said tone arm in said T-piece when the tone arm has been moved into the position in which it lies within said deflector.

4. In a talking machine of the type referred to, the combination of a casing, a cover hinged thereon, a bowl-shaped deflector mounted in said cover and arranged with its axis transverse to said cover, a short trumpet within the bowl of and secured to 30 said deflector with one end in alinement with the axis of said deflector, a hollow T-piece pivoted to the other end of said trumpet, a tone arm having one end pivoted to said T piece and a set screw fitted to said 35 tone arm and adapted to project through a slot in said hollow T piece.

In testimony whereof I affix my signature in presence of two witnesses.

WILFRED SAMPSON SAMUEL.
